UNITED STATES PATENT OFFICE.

GEORGE C. BECKWITH, OF CAMBRIDGE, MASSACHUSETTS, ASSIGNOR TO E. D. MELLEN, OF SAME PLACE, AND ISAAC H. DAVIS, OF BOSTON, MASSACHUSETTS.

DESIGN FOR A MOTOR-FRAME FOR ENGINES.

SPECIFICATION forming part of Design No. 32,110, dated January 16, 1900.

Application filed November 6, 1899. Serial No. 736,052. Term of patent 14 years.

To all whom it may concern:

Be it known that I, GEORGE C. BECKWITH, of Cambridge, in the county of Middlesex and State of Massachusetts, have invented and produced a certain new and original Design for a Motor-Frame for Engines, of which the following is a specification, reference being had to the accompanying drawings, forming a part thereof.

Figure 1 is a side elevation of a motor-frame, showing my new design. Fig. 2 is an end elevation of the same.

As shown in the drawings, the leading or material feature of my design consists of a series of transverse flanges $a a a' a'$, the flanges

$a a$ being at the ends of the central section b of the motor, while the flanges $a' a'$ are at the outer ends of the sections $b' b'$, and the longitudinal rods $c c c c$, extending through and at right angles with the flanges $a a a' a'$ and relatively arranged, as shown in the drawings.

I claim--

The design for a motor-frame for engines, substantially as shown and described.

In testimony whereof I have affixed my signature in presence of two witnesses.

GEORGE C. BECKWITH.

Witnesses:

C. F. BROWN,

A. D. HARRISON.
